(57) **CLAIM**

The ornamental design for a television receiver, as shown and described.

DESCRIPTION

1. Television receiver

1.1 : Front perspective view

1.2 : Rear perspective view

1.3 : Front view

1.4 : Rear view

1.5 : Left view

1.6 : Right view

1.7 : Top view

1.8 : Bottom view

1.9 : Partial enlarged front perspective view, demonstrating the camera door in an open state

1.10 : Partial enlarged front perspective view, demonstrating the camera door in a closed state

The dash-dash broken lines depict portions of the television receiver that form no part of the claimed design. The dot-dot-dash broken lines in reproductions 1.9 and 1.10 are included for the purpose of illustrating the partial enlargements and form no part of the claimed design.

1 Claim, 10 Drawing Sheets
